UNITED STATES PATENT OFFICE.

CHARLES J. PILLING, OF LANSDOWNE, PENNSYLVANIA, ASSIGNOR TO GEORGE P. PILLING AND CHARLES J. PILLING, OF PHILADELPHIA, PENNSYLVANIA, COPARTNERS TRADING AS GEORGE P. PILLING & SON.

DESIGN FOR A BLANK FOR SPECULUM-BLADES.

SPECIFICATION forming part of Design No. 35,716, dated February 11, 1902.

Application filed January 16, 1902. Serial No. 90,097. Term of patent 7 years.

To all whom it may concern:

Be it known that I, CHARLES J. PILLING, a citizen of the United States, residing at Lansdowne, State of Pennsylvania, have invented and produced a certain new and original Design for a Blank for Speculum-Blades, of which the following is a full, clear, and exact description, reference being had to the accompanying drawings, forming a part of this specification.

Figure 1 is a side elevation of the blank, and Fig. 2 an edge view thereof.

My invention consists of the design, in novel outline planular shape or configuration, shown in said drawings, of a sheet-metal blank from which the upper blades of a trivalvular speculum may be "struck up" by dies, as is usual with sheet-metal blanks. In its essentials it comprises a blade portion A and han-

dle portion B. At the junction of the two the blank is curved on both sides, with a full curve a on the outside and a shorter curve a' on the inside of the bend. The handle portion B has a swell on each side (indicated at b b') and at the extreme end, on the inner side, has a slightly-enlarged end b^2 , forming a lip on one side.

I claim as new—

The design for a blank for a trivalvular speculum-blade, substantially as shown and described.

In testimony whereof I have hereunto affixed my signature this 15th day of January, A. D. 1902.

CHARLES J. PILLING.
